UNITED STATES PATENT OFFICE.

FRANK S. BAIRD, OF PHOENIX, ARIZONA, ASSIGNOR OF ONE-HALF TO G. EDWARD GARNER, OF PHOENIX, ARIZONA.

CURRENT-PROPELLED HYDROPLANE.

1,279,218.

Specification of Letters Patent. Patented Sept. 17, 1918.

Application filed August 13, 1917. Serial No. 185,938.

To all whom it may concern:

Be it known that I, FRANK S. BAIRD, a citizen of the United States, residing at Phoenix, in the county of Maricopa and State of Arizona, have invented certain new and useful Improvements in Current-Propelled Hydroplanes; of which the following is a specification, reference being had therein to the accompanying drawing.

10 This invention relates to apparatus adapted to be projected across streams of water by the force of the water currents.

Under various circumstances it becomes highly desirable to effect the passage of streams of water where no means are available or effective for that purpose. For example, in the case of rivers, bridges and other means of communication, such as telephone and telegraph wires, are often washed out by floods and the reestablishment of communication during the continuance of the flood conditions is often extremely difficult if not impossible. Again, on salt water, conditions are sometimes encountered where currents set up by the flow of tides, or otherwise, might be utilized by apparatus of the character in question for establishing communication between points separated by the said currents.

15 The prime object of my invention is the production of a buoyant body which is adapted to be projected across flowing streams, such as above referred to, by the force of said streams and without any connection with a fixed abutment in advance of the body as it proceeds across the stream.

Other objects of the invention, which are more or less incidental to the efficient carrying out of the main object above stated, will appear in the following description in which, for purposes of explanation, I set forth in connection with the accompanying drawings a preferred embodiment of the invention.

In the drawings,

Figure 1 is a plan view of a hydroplane embodying the invention.

Fig. 2 is a right side elevation of the same.

Fig. 3 is a vertical section on the line 3—3 of Fig. 1.

Fig. 4 is a fragmentary left side eleva-

tion showing the reversible rudder applied to the left side of the hydroplane.

Fig. 5 is a plan view of a modified form of construction.

Referring first to the construction shown in Figs. 1 to 4, inclusive, the main body of the hydroplane comprises a central longitudinal member 1 and a transverse member 2 rigidly secured thereto by bolts or nails 3. In the construction shown the parts 1 and 2 are made of any suitable wood. The longitudinal member 1 is relatively narrow and deep and, when the plane is placed in the water, presents relatively deep upright lateral surfaces 1^a to the water. At its front end the member 1 has its corners beveled at 1^b so that the friction of the water on the front end of the plane is reduced to a minimum.

The transverse member 2 of the plane is preferably disposed somewhat in front of the middle of the longitudinal member 1 with its width approximately horizontal. This transverse member is made of a length sufficient to give the plane lateral stability, and preferably its bottom surface 2^a is inclined downwardly and rearwardly for a purpose which will later be explained.

The body of the hydroplane is preferably provided at its rear end with a rudder which tends to direct the longitudinal member of the plane across currents of water in which the plane floats. In the construction shown the rudder is in the form of a combined rudder and stabilizing device designated as an entirety by 4. This device is formed preferably of sheet metal which is bent to form an upright rudder vane 4^a and a horizontal stabilizing vane 4^b. The rudder vane 4^a is bent on a central vertical line, as indicated in Fig. 3, and is formed with two holes 4^c, 4^d, one near each end of the rudder. The device is operatively secured to the body of the hydroplane by means of a bolt 5, as indicated in Fig. 1, or as indicated in Fig. 4. In Fig. 1 the device is applied to the right side of the longitudinal member 1, while in Fig. 4 the device is turned end for end and applied to the left side of the member 1.

The hydroplane is provided with a fastening device 6 for a flexible tension member such as a rope, cord or wire, the device, in

the construction shown, being in the form of an arm mounted on a pivot 7 and secured rigidly but adjustably in fixed relation to the body of the hydroplane by a pin 8 which 5 is slidably mounted in the arm 6 in position to engage any one of a series of apertures 9, 9 in the transverse member 2 of the plane. At its outer end the arm 6 is formed with an aperture 6^a to which the rope 10, or other 10 flexible tension member, can be secured. By angular adjustment of the arm 6 the point of attachment of the tension member 10 to the hydroplane can be adjusted through a considerable range. Also the transverse 15 member 2 is formed on its right side with a series of apertures 9^a so that the arm 6 can be swung 180° and secured in operative position on the right side of the hydroplane when the latter is to move in the reverse 20 direction.

For the purpose of strengthening the body of the hydroplane, I prefer to connect the ends of the transverse member 2 with the two ends of the longitudinal member 1 by 25 means of a wire 11 of suitable weight, the several sections of which, when drawn taut, serve to gradually strengthen the structure. This wire 11 can be formed adjacent one end of the transverse member 2 with a series of 30 loops 12 and adjacent the other end of the transverse member with a similar series of loops 12^a, each of which constitutes a suitable fastening device by means of which the rope 10 can be secured to the hydroplane. 35 By selecting different fastening loops the connection of the tension member 10 can be varied or adjusted through a considerable range, and these fastening loops can be employed either in lieu of the fastening device 40 6 or for the purpose of affording a supplemental range of adjustment for the connection of the tension member 10.

In the use of the apparatus above described, it is launched in the water with its 45 beveled front end 1^b up stream and with the longitudinal member somewhat across the current. The parts of the hydroplane are so proportioned and related with respect to their specific gravity that the central longitudinal member has its entire depth submerged, while the transverse member 2 is 50 also slightly submerged. It will be seen, therefore, that as the operator starts the hydroplane into the current in the position 55 stated, with the rope or line 10 in hand to be gradually paid out, the force of the current, the direction of which is indicated by the arrow in Fig. 1, striking the deep lateral surface of the longitudinal member 1 of the 60 plane, tends to swing the front end of the plane around in the current, but is prevented from doing so by the draft of the tension member 10. The resultant of the two forces mentioned, that is the current and the draft 65 of the tension member 10, tends to urge the

hydroplane across the stream away from the operator who, by gradually paying out the rope or cord 10, can cause the hydroplane to gradually traverse the full width of the stream. 70

In operation the stability of the plane about its longitudinal axis is insured by the transverse member 2; and said transverse member, by virtue of its inclined bottom surface, utilizes the force of the current to produce a substantial lifting action upon the hydroplane which supplements its inherent buoyancy and thereby makes it possible to reduce the submergence of the transverse 75 stabilizing member 2 to a minimum, and correspondingly reduce the frictional down stream drag of the current on the hydroplane. 80

It will be obvious that the rudder 4^a tends in the operation of the hydroplane to direct 85 the stream into operative position, thus both facilitating the launching of the apparatus into operative position and its maintenance in such operative position after it has passed 90 away from the operator and is subject to his control only through the tension member 10.

The horizontal stabilizing vane 4^b of the rudder device 4 acts to minimize pitching of the plane and thus helps to maintain it 95 steadily in working position.

An apparatus of this character can be used very successfully and advantageously in carrying a wire across a swollen river where means of communication have been washed 100 out, and it will be understood that by adjusting the point of connection of the tension member 10 to the hydroplane, the latter can be caused to move more or less down the stream as it advances across it, and thus advantage can be taken of the most advantageous point for launching the apparatus on one side of the stream and for receiving it on the other. 105

By connecting the tension member 10 to 110 the right side of the hydroplane instead of to the left side and by reversing the rudder device 4 and applying it to the left side of the hydroplane, as shown in Fig. 4, the apparatus can readily be fitted to traverse a 115 stream in the opposite direction from that indicated in Fig. 1.

In Fig. 5 of the drawing I have shown a modified form of construction in which use is made of two longitudinal members 21 arranged parallel to each other, and two transverse members 22 which are spaced apart, as shown, and rigidly secured to the longitudinal members 21. Both the members 21 and 22 are shaped in substantially the same 12 fashion as the corresponding members 1 and 2 in Fig. 1, and as in the latter case, the structure is braced by a wire 23 which joins the ends of the members 21 and 22 as indicated. The hydroplane is formed with a 12

rudder and stabilizing device 24 similar to the device 4 previously described, and the rudder device 24 can be applied to the right longitudinal member 21, as shown, or can be reversed and applied to the left member 21 when the hydroplane is to travel in the opposite direction. In the present construction, I have shown the flexible tension member 25 provided with branches 25^a, 25^b, which are secured at 26 and 27 to the body of the hydroplane. The wire 23 is also formed with loops 28 and 28^a which constitute alternative means for connecting the tension member 25 to the body of the plane.

15 In Fig. 5 the large arrow indicates the direction of the current and, as will be readily understood, the operation of the apparatus is similar in all respects to that of the apparatus shown in Fig. 1.

20 It will be understood that the foregoing description and the disclosure in the drawing are solely for the purpose of explanation and illustration and are not to be construed in a limiting sense. It is obvious that many 25 widely varying modifications of the constructions shown can be effected without departing from my invention. Also an apparatus of this character can be put to numerous uses other than those mentioned. In 30 particular, its adaptability as a toy and for purposes of sport will be readily appreciated.

What I claim is:

1. In apparatus of the character described, 35 the combination of a body adapted to sustain itself in a stream of water and comprising an elongated part having relatively deep longitudinally extending lateral surfaces adapted when lying across the current 40 of the stream to strongly resist the same and means for giving the body lateral stability so as to maintain the said lateral surfaces in upright position, and fastening means for a flexible tension device so disposed on the 45 said body that the draft of a flexible tension device secured thereto acts to hold the body with its said lateral surfaces across the current of the stream while the resultant of the 50 forces of the current and the tension device on the body impels it across the stream as the tension device is paid out.

2. In apparatus of the character described, 55 the combination of a buoyant body adapted to sustain itself in a stream of water and having relatively deep longitudinally extending lateral surfaces adapted when lying across the current of the stream to strongly resist the same and having also parts extending laterally from the said longitudinal surfaces whereby the latter are stably maintained in upright position, and fastening means for a flexible tension device so disposed on the said body that the draft of a flexible tension device secured thereto acts to hold the body with its lateral surfaces across the current of the stream while the 60 resultant of the forces of the current and the tension device on the body impels it across the stream as the tension device is paid out.

6. In apparatus of the character described, 65 the combination of a body adapted to sustain

across the current of the stream while the resultant of the forces of the current and the tension device on the body impels it across the stream as the tension device is paid out.

3. In apparatus of the character described, 70 the combination of a buoyant body adapted to sustain itself in a stream of water and comprising an elongated part having relatively deep longitudinally extending lateral 75 surfaces adapted when lying across the current of the stream to strongly resist the same, means for rendering the said body stable with respect to its longitudinal axis and its transverse axis, and fastening means for a 80 flexible tension device so disposed on the said body that the draft of a flexible tension device secured thereto acts to hold the body with its said lateral surfaces across the current of the stream while the resultant of the 85 forces of the current and the tension device on the body impels it across the stream as the tension device is paid out.

4. In apparatus of the character described, 90 the combination of a body adapted to sustain itself in a stream of water and comprising an elongated part having relatively deep longitudinally extending lateral surfaces adapted when lying across the current of the stream to strongly resist the same and 95 means for giving the body lateral stability so as to maintain the said lateral surfaces in upright position, additional means for rendering the said body stable with respect to its transverse axis, and fastening means for 100 a flexible tension device so disposed on the said body that the draft of a flexible tension device secured thereto acts to hold the body with its said lateral surfaces across the current of the stream while the resultant of 105 the forces of the current and the tension device on the body impels it across the stream as the tension device is paid out.

5. In apparatus of the character described, 110 the combination of a buoyant body adapted to sustain itself in a stream of water and having relatively deep longitudinally extending lateral surfaces adapted when lying across the current of the stream to strongly resist the same and having also parts extending laterally from the said longitudinal surfaces whereby the latter are stably maintained in upright position, means at the rear end of said body for rendering it stable with respect to its transverse axis, and fastening means for a flexible tension device so disposed on the said body that the draft of a flexible tension device secured thereto acts to hold the body with its said lateral surfaces across the current of the stream while the 115 resultant of the forces of the current and the tension device on the body impels it across the stream as the tension device is paid out.

6. In apparatus of the character described, 120 the combination of a body adapted to sustain

itself in a stream of water and comprising an elongated part having relatively deep longitudinally extending lateral surfaces adapted when lying across the current of the stream to strongly resist the same and means for giving the body lateral stability so as to maintain the said lateral surfaces in upright position, a rudder device which tends to direct the said body across the current of the stream, and fastening means for a flexible tension device so disposed on the said body that the draft of a flexible tension device secured thereto acts to hold the body with its said lateral surfaces across the current of the stream while the resultant of the forces of the current and the tension device on the body impels it across the stream as the tension device is paid out.

7. In apparatus of the character described, the combination of a buoyant body adapted to sustain itself in a stream of water and having relatively deep longitudinally extending lateral surfaces adapted when lying across the current of the stream to strongly resist the same and having also parts extending laterally from the said longitudinal surfaces whereby the latter are stably maintained in upright position, the said laterally extending parts having their bottom surfaces inclined upwardly and forwardly, and fastening means for a flexible tension device so disposed on the said body that the draft of a flexible tension device secured thereto acts to hold the body with its said lateral surfaces across the current of the stream while the resultant of the forces of the current and the tension device on the body impels it across the stream as the tension device is paid out.

40 8. In apparatus of the character described, the combination of a body adapted to sustain itself in a stream of water and comprising an elongated part having relatively deep longitudinally extending lateral surfaces adapted when lying across the current of the stream to strongly resist the same and means for giving the body lateral stability so as to maintain the said lateral surfaces in upright position, and fastening means for a flexible tension device adjustably arranged on the said body so that the direction of the draft of a flexible tension device secured thereto can be adjusted to hold the body with its said lateral surfaces across the current of the stream and to cause the resultant of the forces of the current and the tension device on the body to impel it in a desired direction across the stream as the tension device is paid out.

60 9. In apparatus of the character described, the combination of a body adapted to sustain itself in a stream of water and comprising an elongated part having relatively deep longitudinally extending lateral surfaces adapted when lying across the current

of the stream to strongly resist the same and means for giving the body lateral stability so as to maintain the said lateral surfaces in upright position, and fastening means for a flexible tension device so disposed on the said body that the draft of a flexible tension device secured thereto acts to hold the body with its said lateral surfaces across the current of the stream while the resultant of the forces of the current and the tension device on the body impels it across the stream as the tension device is paid out, the said fastening means being adapted to secure the flexible tension device either to the left or to the right side of the body whereby the apparatus can be caused to traverse a stream in either direction.

10. In apparatus of the character described, the combination of a body adapted to sustain itself in a stream of water and comprising an elongated part having relatively deep longitudinally extending lateral surfaces adapted when lying across the current of the stream to strongly resist the same and means for giving the body lateral stability so as to maintain the said lateral surfaces in upright position, a rudder device which tends to direct the said body across the current of the stream, and fastening means for a flexible tension device so disposed on the said body that the draft of a flexible tension device secured thereto acts to hold the body with its said lateral surfaces across the current of the stream while the resultant of the forces of the current and the tension device on the body impels it across the stream as the tension device is paid out, the said fastening means being adapted to secure the flexible device to either the left side or the right side of the said body and the rudder device being reversible, whereby the apparatus can be caused to traverse a stream in either direction.

11. In apparatus of the character described, the combination of a buoyant body adapted to sustain itself in a stream of water and comprising a long, narrow longitudinal member with deep lateral surfaces and an elongated transverse member extending from either side of the longitudinal member and rendering the body stable about its longitudinal axis, and fastening means for a flexible tension device so disposed on the said body that the draft of a flexible tension device secured thereto acts to hold the body with its said lateral surfaces across the current of the stream while the resultant of the forces of the current and the tension device on the body impels it across the stream as the tension device is paid out.

12. In apparatus of the character described, the combination of a buoyant body adapted to sustain itself in a stream of water and comprising a long, narrow longitudinal member with deep lateral surfaces

- and an elongated transverse member extending from either side of the longitudinal member and rendering the body stable about its longitudinal axis, means for strengthening said body comprising a taut tension device extending from each end of the longitudinal member to each end of the transverse member, and fastening means for a flexible tension device so disposed on the said body
- 5 that the draft of a flexible tension device secured thereto acts to hold the body with its said lateral surfaces across the current of the stream while the resultant of the forces of the current and the tension device on the body impels it across the stream as the tension device is paid out.
- 10 13. In apparatus of the character described, the combination of a buoyant body adapted to sustain itself in a stream of water and comprising a long, narrow longitudinal member with deep lateral surfaces and an elongated transverse member extending from either side of the longitudinal member and rendering the body stable about its longitudinal axis, said transverse member having its bottom surface inclined upwardly and forwardly.
- 15 14. In apparatus of the character described, the combination of a buoyant body adapted to sustain itself in a stream of water and comprising a long, narrow longitudinal member with deep lateral surfaces and an elongated transverse member extending from either side of the longitudinal member and rendering the body stable about
- its longitudinal axis, and means on the rear end of the longitudinal member for guiding the body across the current of the stream and for opposing pitching of the body around the transverse axis, and fastening means for a flexible tensioning device so disposed on the said body that the draft of a flexible tension device secured thereto acts to hold the body with its lateral surfaces across the current of the stream while the resultant of the forces of the current and the tension device on the body impels it across the stream as the tension device is paid out.
- 20 15. In apparatus of the class described, the combination of a body adapted to sustain itself in a stream of water and comprising an elongated part having relatively deep longitudinally extending lateral surfaces adapted when lying across the current of the stream to strongly resist the same and means for giving the body lateral stability so as to maintain the said lateral surfaces in upright position, and a flexible tension device connected to the said body so that its draft thereon acts in conjunction with the force of the current to hold the body with its lateral surfaces across the current of the stream while the resultant of the forces of the current and the tension device on the body impels the latter across the stream as the tension device is paid out.
- 25 In testimony whereof I hereunto affix my signature.
